METHOD AND FASHIONING MEANS FOR
KNITTING MACHINES

Herbert Erich Haehnel, West Reading, Pa., assignor to Textile Machine Works, Wyomissing, Pa., a corporation of Pennsylvania

Application June 18, 1948, Serial No. 33,748

32 Claims. (Cl. 66—89)

1

The present invention relates to knitting machines having fashioning mechanism adapted to widen the fabric by point comb transfer of loops and to a method of operating such machines.

One method of widening full-fashioned knitted fabric involves the outward transfer of loops by point transfer combs, and the moving of the end stops of the yarn carrier or carriers out or in the widening direction at the same average rate as the point combs. In operating according to this method, it has been the custom always to move the nut carrying the end stops in revolutions in which the combs are moved and in which therefore, the friction box rod of the coulier means is stationary.

In moving the end stop nut in the widening direction, the carrier rod or rods, laying yarn in the widened area, are engaged to and moved with the end stop nut. Upon the outward movement of the nut and carrier rods, the friction boxes, connected to the carrier rods and in frictional engagement with the friction rod, must also be moved. Therefore, the nut, in overcoming not only the weight of the carrier rods and friction boxes, but also the friction between the boxes and the friction rod, exerts considerable drag on its spindle resulting in wear between the nut and spindle, this wear causing a misalignment of the yarn carriers on the carrier rods and the sinkers and dividers of the machine. While the wear to the nut and spindle may be overcome by adjustments to the parts, in many instances such wear is not known until the yarn carriers become sufficiently misaligned with the sinkers and dividers to cause damage to these parts.

It is therefore an object of the present invention to remove the cause of wear and its resultant troubles when operating to widen full-fashioned fabric by the joint action of end stops and point transfer combs.

A second object of the invention is to provide a means for widening by joint action but whereby it will be unnecessary to move the end stops at times when the coulier means is stationary.

Another object of the invention is to provide means for widening by joint action but whereby the point transfer combs may be prevented from moving at the same time as the end stops.

A further object of the invention is to provide means for carrying out a repetitive cycle of end stop movements and point transfer movements in which the end stops will make two needle widening steps during the knitting cycles and the

2

transfer points will make single needle widening steps in fashioning cycles but the two movements will be coordinated to keep the stops and points substantially in the same relative positions throughout the formation of a widened section of a blank.

It is becoming increasingly popular to use single needle narrowing throughout the leg portions of full-fashioned stocking blanks while retaining the use of the formerly almost exclusively used two needle narrowing in the sole and toe portions and it is a still further object of the invention to provide a full-fashioned knitting machine having narrowing mechanism which is adapted to cause either single needle or two needle narrowing and which operates to automatically change from two needle to single needle operation.

With these and other objects in view, which will become apparent from the following detailed description of the form of the invention shown in the accompanying drawings, the present invention resides in the novel elements, features of construction, arrangement of parts in cooperative relationship and method of operation as hereinafter more particularly pointed out in the claims.

In the drawings:

Figure 1 is an elevational view of a portion of the left end of a "Reading" type full-fashioned knitting machine having the present invention incorporated therein;

Fig. 2 is a view similar to a portion of Fig. 1 but on a larger scale and with certain parts shown in different relative positions;

Fig. 3 is an elevational view as seen from the right of Fig. 2, parts being omitted and parts being broken away for purposes of illustration;

Fig. 4 is an elevational view as seen from the left of Fig. 2;

Fig. 5 is a fragmentary front elevation of the same end of the machine as is shown in Fig. 1 and to approximately the same scale, showing certain of the control mechanism according to the invention, certain parts being broken away and others shown in dotted outline for purposes of illustration;

Fig. 6 is a detailed view partially in section taken substantially along the line 6—6 of Fig. 9;

Fig. 7 is a detailed view partially in section taken substantially on the line 7—7 of Fig. 6;

Fig. 8 is an elevational view of the mechanism shown in Fig. 7, looking in the direction of the arrows 8—8;

Fig. 9 is a plan view taken substantially along the line 9—9 on Fig. 5, certain parts being omitted;

Fig. 10 is a detailed view taken substantially on the line 10—10 of Fig. 9;

Fig. 11 is a detailed view of certain of the mechanism shown in Fig. 2, showing certain of the control mechanism for the spindle racking pawls, parts being omitted and other shown in section for purposes of illustration;

Fig. 12 is a fragmentary detailed view taken in the direction of the arrows 12—12 on Fig. 11;

Fig. 13 is a view similar to a portion of Fig. 11 with the parts shown in different relative positions;

Fig. 14 is a detailed sectional view taken substantially along the line 14—14 of Fig. 11; and

Fig. 15 is a view similar to Fig. 14 with the parts shown in different positions relative to Fig. 14 and taken on the line 15—15 of Fig. 13.

In the drawings and description, only the means and method necessary to a complete understanding of the invention are specifically set forth; further information as to the construction and operation of other related, usual and well known knitting machine elements, mechanisms, etc., may be found in one or more of the following publications:

1. Pamphlet entitled, "Full-Fashioned Knitting Machines," published and copyrighted by the Textile Machine Works, Reading, Pennsylvania, in 1920.

2. Four catalogs entitled, "The 'Reading' Full-Fashioned Knitting Machine Parts Catalog," published and copyrighted by the Textile Machine Works, in 1929, 1935, 1940, and 1947, respectively.

3. Booklet entitled, "The 'Reading' High Production Full-Fashioned Knitting Machine," which, forming a supplement to the above noted 1940 parts catalog of the Textile Machine Works, is a publication of the Textile Machine Works, copyrighted by the latter in 1940.

4. Pamphlet entitled, "Knitting Machine Lectures," published by the Wyomissing Polytechnic Institute, Wyomissing, Pennsylvania, in 1935.

A knitting machine within the invention comprises a needle bar and fashioning means including movable end stops for the yarn carrier rods, said stops being moved to narrow and widen in steps equal to twice the distance between next adjacent needles because of the structure and relation of the usual carriers, sinkers and dividers used in such machine. Loop transferring points, also a part of the fashioning means, are moved in two needle steps in the narrowing direction but are adapted to be moved in single needle steps both in the narrowing and widening directions as hereinafter set forth. When narrowing or widening in single needle steps it is desirable, in most instances, to maintain the points in a definite relation to the selvages and end stops throughout the single needle step operations. For this purpose, means are provided to prevent operation of the end stops in alternate narrowing and widening operations. The machine within the invention also is provided with means for operating the end stops to widen during a couloring or knitting operation and the points in a succeeding or narrowing operation of the machine and includes means for preventing the operation of the transfer points during operation of the end stops and preventing operation of the end stops during operation of the points. The machine is also provided with means associated

with the transfer points for preventing the points from moving beyond predetermined limits as hereinafter set forth.

The mechanism shown in the drawings is a part of a multi-section type full-fashioned knitting machine and comprises a usual framework including end frames, one of which is shown at 22, which are joined to center frames (not shown) by a back beam 24 and a front beam 26, Figs. 1, 5 and 9. A main camshaft 20, journaled in end frames 22 and the center frames, carries cams for actuating the loop forming and other mechanisms of the machine in the usual and well known manner.

Carried on the framework at the left end of the machine in the usual manner is a narrowing head mechanism 25, there usually being two such mechanisms, one at either end of the machine. The mechanism 25 includes a threaded spindle 34 for determining the positions of end stops 36, Figs. 1 and 4, for limiting the endwise extent of movement of the yarn carrier rods, not shown, and a spindle 38 for determining the position of narrowing rods 40, shown in Fig. 3, on which the transfer or narrowing points are mounted. The end stops 36, are pivotally mounted on a nut 37 carried on the threaded portion of spindle 34 (Fig. 4). The spindle 38 is provided with oppositely threaded portions, each of which carries a nut 39, only the left hand nut being shown in Fig. 3, associated with and moving the narrowing rods 40 in the usual manner. Two of the rods 40 carry wide transfer point combs and the other rods 40 carry narrow point combs (not shown), the rods having a wide and a narrow comb respectively cooperating with the left nut 39 and the other rods with their associated wide and narrow combs cooperating with the right nut (not shown). Each wide comb acts independently or at times cooperates with one of the narrow combs to fashion the selvage edges of the blank in the usual manner.

Racking impulses for turning the spindle 34 and spindle 38 are delivered to the spindles from the main camshaft 20 through a train of mechanism which includes cams 44 and 46 on the camshaft and a cam follower 48, Fig. 1. In the arrangement according to the present invention, cam 44 is used when it is desired to turn both spindles 34 and 38 in the narrowing or widening directions during a narrowing cycle while cam 46 is used when it is desired to turn spindle 34 only in the widening direction during a knitting or loop forming cycle, counterclockwise as viewed in Fig. 1. Means hereinafter set forth, are provided to prevent certain of the impulses from cam 44 from affecting spindle 34 and to prevent the impulses from cam 46 from affecting spindle 38. Except in revolutions of the camshaft 20 in which fashioning is to be performed, the follower 48 is maintained out of the planes of said cams 44 and 46 and in the position shown in Figs. 5 and 9. Where a fashioning movement of the end stops is to be performed during a knitting revolution of the main camshaft, follower 48 is shifted to the plane of cam 46 to cooperate therewith while if a movement of the end stops or transfer points or both is or are to be performed during a non-knitting or "narrowing" revolution of the cam shaft, the follower 48 is not shifted but an equivalent effect is produced by shifting or "shogging" the camshaft to bring the cam 44 into the same plane as the follower 48.

An impulse from cam 44 or cam 46 is transmitted first to cam follower 48 which is mounted

to revolve on a pin 50 and also to slide lengthwise of the pin. Pin 50 is fixed intermediate the ends of a lever 52 which is pivoted at its front end at 54 in transverse end frame 22. Lever 52 is provided with a stud or axle 56 fixed thereon on which is pivotally mounted an actuator 60, the lower end of the actuator resting on a bolt 63 supported on the end frame 22 to limit the lowermost position of the follower 48 relative to cams 44, 46 and camshaft 20, Fig. 1. The actuator 60 is connected to pawls cooperating with ratchet wheels for turning spindles 34 and 38 as hereinafter set forth.

The spindles 34 and 38 are turned in the narrowing direction by pawls 58 and 61, respectively, as shown in Figs. 1, 2 and 11, pawls 58 and 61 being pivotally carried on levers 74 and 76 in turn pivotally mounted on the spindles 34 and 38, respectively. The levers 74 and 76 are connected to the actuator 60 in the usual manner. The spindles 34 and 38 are turned in the widening direction by pawls 62 and 64, respectively, which are connected to the actuator 60 as shown in Fig. 2. The pawls 58 and 61 cooperate with ratchet wheels 66 and 68 on the spindles 34 and 38, respectively (Fig. 11), and the pawls 62 and 64 cooperate with ratchet wheels 70 and 72 on the spindles 34 and 38, respectively. The ratchet wheels 66 and 70 are provided with teeth having a spacing equal to a two needle turning movement of the spindle 34 and the ratchet wheels 68 and 72 are provided with teeth having a spacing equal to a one needle turning movement of the spindle 38, in the usual manner. All of said pawls act only on upstrokes of each operating movement of actuator 60, a fifth pawl 71 being shown for a purpose hereinafter set forth, pawl 71 acting on ratchet 72 on spindle 38 in the widening direction but on the downstroke only of the actuator.

Narrowing pawls 58 and 61 both receive impulses from cam 44 at the same time during revolutions of the camshaft in which narrowing is performed. At such times, the pattern means throws into action a mechanism (not shown) which shifts shaft 20 from left to right, in the usual manner, as viewed in Fig. 9. The follower 48 being held at such times in the same plane as in knitting revolutions, cam 44 is shifted along with shaft 20 so that it comes into the same plane as follower 48. The follower lever 52, actuator 60 and pawls 58 and 61 are then all lifted by the cam and, the mechanism being set for two needle narrowing, spindle 34 is turned through a distance equal to one tooth of the ratchet 66 and spindle 38 is simultaneously turned through a distance equal to two teeth of the ratchet 68 to move the nuts 37 and 39, respectively, a distance of two needles, that is, one equal to twice the distance between next adjacent knitting needles of the machine. When it is desired to fashion by single needle narrowing, a plate cam 71, pivoted on spindle 38 is provided to hold the pawl 61 away from the first tooth but permitting the pawl to engage the second tooth in its path to turn the spindle 38 a one needle distance. The spindle 34, however, is turned a two needle distance at the time spindle 38 is turned only a one needle distance and it being desired to maintain a substantially constant relation between the positions of the end stops and the transfer points, means is provided whereby pawl 58 is held out of action every other narrowing revolution. A similar situation occurs when widening. The spindle 38 moving only a one needle distance for each individual widening operation of spindle 76

38, the spindle 34 is prevented from turning in alternate widening operations of spindle 38 by holding pawl 62 out of action. In the arrangement shown, the means for holding pawls 58 and 62 out of action at desired times are combined with still another means, one for holding pawl 64 out of action. Said entire means will be described in detail hereinbelow.

As all the four pawls so far described act on the upstroke of actuator 60, and as all are necessarily normally biased toward their ratchet wheels, it is necessary to keep the widening pawls from engaging their ratchet wheels during revolutions in which narrowing is to be performed and necessary to keep the narrowing pawls from engaging their ratchets when widening is to be performed. For these purposes, plate cams 78 and 80 are pivoted one on spindle 34 and one on spindle 38, respectively, as shown in Fig. 2. Cams 78 and 80 are positioned and operated by a means including a link 82 pivotally connected to cam 78, cams 78 and 80 being pivotally connected in fixed relation to each other by a link 84. Normally, cams 78 and 80 lie in positions shown in Fig. 1 and in which the narrowing pawls 58 and 61 are free to act on their ratchets while the widening pawls 62 and 64 are held inactive, cam 78 contacting a part of widening pawl 62 and cam 80 contacting a part of pawl 64. When cams 78 and 80 are turned on their spindles to the positions shown in Fig. 2, cam 78 contacts a part of pawl 58 to disable said pawl. However, cam 80 does not act on narrowing pawl 61, but pawl 61 is disabled by cam 78 through a lost motion connection with pawl 58 comprising a linkage pivoted to downwardly extending portions of the pawls and including a member 79 shown as connected directly to pawl 61 and having a sliding connection with a member 81 which is connected directly to pawl 58. It will be seen in Fig. 2 that cam 80 is so formed that it permits pawl 64 to move its ratchet 72 and spindle 38 only a single needle distance per upward stroke of the pawl.

For turning cams 78 and 80 to disable pawls 58 and 61 and free pawls 62 and 64, said link 82 is pivotally connected at its lower end to one arm 86 of a bell-crank lever 88 pivotally mounted on end frame 22, Figs. 5 and 9, and which has a downwardly extending arm 90. The lower end of arm 90 is pivoted to a link 92 which extends alongside the back beam 24 to a pivotal connection with a downwardly extending arm 94 of a bell-crank lever 96 pivotally mounted on a bracket 98 fixed to said back beam. Lever 96 has an arm 99 having a pin 100 therein on which is a roller type follower 102, Figs. 7 and 8, contacting a cam surface on a cam member 104. A spring 95 connected to the arm 99 and the back beam 24, biases the levers 88 and 96 in a counterclockwise direction (Figs. 5 and 6) to maintain engagement between the follower 102 and cam member 104. Member 104 is provided with extensions 105, as shown in Figs. 6, 7 and 8, fixed to a rod 106 which extends along substantially the entire length of the machine so as to control both narrowing heads. The member 104 is guided in its movement with rod 106 in a bifurcated portion 101 of bracket 98 (Fig. 7) and by the engagement of one of the extensions 105 and a projecting portion 103 of the bracket, as shown in Figs. 6, 7 and 8. A set screw 108 carried on the portion 103 cooperates with the arm 94 of the lever 96 to limit the counterclockwise movement of the lever, as viewed in Fig. 8, when turned by the cam 104. Rod 106 is operated at desired times

in the direction of its length by a pattern controlled means from right to left, as viewed in Fig. 6, or from left to right, as viewed in Fig. 8, to thrust the high part of cam 104 beneath roller 102 to thereby turn arm 94 of lever 96 in the clockwise direction (Fig. 6) to move lever 88 in the clockwise direction as viewed in Fig. 5 to thereby operate link 82 and turn cams 78 and 80 from the positions shown in Fig. 1 to the positions shown in Fig. 2. The rod 106 is given different length movements by the pattern controlled means, for purposes hereinafter set forth, each movement, irrespective of its length, operating the link to turn the cams 78 and 80.

When the rod 106 is given the shorter of its different length movements to the left, as viewed in Fig. 6, the link 82 shifts the cams 78 and 80 without affecting the position of the cam follower 48. Thereupon, shifting of the cam shaft 20 to its narrowing position aligns the cam 44 with the follower 48 to cause the widening action. When the rod 106 is given the longer of its movements, the cam follower 48 is shifted into alignment with the cam 46 simultaneously with the shifting of the cams 78 and 80 thereby causing the widening action in a knitting cycle.

Rod 106 is arranged to shift follower 48 by means of a lever 107 pivotally carried at 113 on the back beam 24, one end 109 of the lever extending between spaced collars 110 and 111 on the rod, as shown in Figs. 5 and 6. The rod is normally biased to the right, as viewed in Fig. 6, to hold the collar 111 in contact with the end 109 of the lever 107 by a spring 114 which surrounds the rod and lies between a collar 116 on the rod and a bracket 118 fixed to back beam 24. Another end 112 of lever 107 is forked to embrace the edge of follower 48, the lever 107 being biased by a spring 97 connected to the lever and the back beam 24 as shown in Figs. 5 and 9, to hold the follower in the position shown in Fig. 5 and in which it can receive an impulse from cam 44 when the shaft 20 is shogged to the right as in a fashioning cycle. As is clearly shown in Figs. 5 and 6, collars 111 and 110 are spaced along rod 106 so that the rod may move the shorter of its different movements or the distance between the right edge of the end 109 of lever 107 and the left edge of collar 110, as viewed in said figures, without affecting lever 107 and thereby follower 48. Whenever, however, rod 106 makes the longer of its different movements from right to left, as hereinbefore set forth, the collar 110 engages lever 107 to turn it about the pivot point 113 of the lever with the consequent shifting of the follower 48 to the right. The cam shaft 20 being held stationary at such times, follower 48 is thereby brought into the plane of cam 46 and actuator 60 is thereby operated during a knitting cycle or revolution.

In order that rod 106 may be moved different distances from left to right at the desired times a means is provided including a lever 115 which is pivoted intermediate its ends at 117 on a bracket 121 fixed to the back beam 24 and is biased to turn clockwise about its pivot as viewed in Fig. 10 by a spring 119. One end of lever 115 is connected to operate rod 106, as shown in Figs. 6 and 10 by means including a link 120 pivotally connected through universal joint members 122 to the lever and to an arm 124 forming part of a bell-crank lever 126 pivotally supported on the bracket 121. The lever 126 has another arm 128 which contacts a collar 130 fixed on rod 106. 75

When lever 115 is permitted to turn in response to spring 119, lever 126 is turned clockwise and rod 106 thrust to the left as will be clear from Fig. 6.

In order that lever 115 may operate rod 106 as desired, the means for controlling and operating the lever is shown as comprising, in addition to the spring 119, a pattern controlled lever 132, as shown in Figs. 5 and 10, which is pivoted to an axle 134 carried on a fixed part of the machine. Intermediate its ends, lever 132 has an arm 136 having one end of a link 138 pivotally connected thereto, the other end of said link being connected to a pattern lever (not shown) adapted to be operated by a button on the main pattern chain to turn lever 132 leftward, that is, counterclockwise as viewed in Fig. 5. Normally, the forward end of lever 115 rests on a land 140 at the upper end of lever 132 and, so long as this is the case, the parts remain in the positions shown in Figs. 1, 5, 6 and 10. When lever 132 is turned counterclockwise by a button on the pattern chain it is moved out from under lever 115 and a follower 141, rotatably carried on the lever 115, engages the high part of a cam 142 on the camshaft 20. As the camshaft is rotated the follower 141 rides from the high to the low peripheral surface of the cam 142 which raises the end of lever 115 connected to the lever 126 and turns the lever 126 in a clockwise direction (Fig. 6) to shift the rod 106 in the longer of its movements. As hereinbefore set forth, the longer movement shifts the collar 110 to the left to engage and turn the lever 107 thereby shifting the follower 48 to the right into alignment with the cam 46, as viewed in Fig. 5. As the cam shaft continues to rotate, the high portion of cam 142 again engages the follower 141 to lift the lever 115, whereupon, with the button having been removed from engagement with the pattern lever in the usual manner, the lever 132 is returned to position beneath the lever 115 to again hold the lever 115 in the position shown in Fig. 10.

In order that the rod 106 may be controlled to make the shorter of its strokes when a button on the pattern chain moves the lever 132 from beneath the lever 115, another button shifts a lever 144, pivotally carried on the axle 134, in a counterclockwise direction, as viewed in Fig. 5, to a position beneath the lever 115. As the follower 141 follows the periphery of the cam 142 from the high to the low surface, the lever 115 is arrested by the lever 144 at a point intermediate the high and low surfaces. With this action the lever 126 is turned through a shorter angle in the clockwise direction whereby the rod 106 is given the shorter of its movements in which the collar 110 is moved to the left, but not sufficiently to engage and turn lever 107, follower 48 thereby remaining in the position shown in Figs. 5 and 9. When the cam shaft 20 is shifted the cam 44 is moved into the plane of the follower 48 whereby the widening operation occurs in a narrowing cycle. The lever 144 is operated from the pattern chain through a rod or link 146 one end of which is connected to a projection 147 on the lever 144 and the other end to a pattern lever of the pattern chain (not shown). During the widening operation the buttons are removed from engagement with pattern levers for levers 132 and 144 whereby the levers return to their position of Fig. 5 with the lever 132 again beneath the lever 115.

As hereinbefore set forth, each long or short

movement of the rod 106 operates the rod 82 to turn the cam 78 and 80 from the positions of Fig. 1 to the positions of Fig. 2 so that an actuation of the actuator 60 operates the pawls 62 and 64 to turn the spindles 34 and 38, respectively. However, when the rod 106 receives the longer of its movements and the widening occurs in a knitting cycle, the pawl 64 must be held away from its ratchet 72 for the full stroke of the actuator 60. When the rod receives the shorter of its movements and the widening occurs in a narrowing cycle, the pawl 62 must be held away from its ratchet wheel 70. The means shown for this purpose comprises bell cranks 148 and 150 pivotally carried on pins 152 and 153 fixed in the end frame 22, one arm 154 of bell crank 148 adapted to engage pawl 64 and one arm 155 of bell crank 150 adapted to engage the pawl 62. A second arm 157 of the bell crank 148 carries an adjustable member 160 and is provided with a spring 162 for biasing the member 160 into engagement with one arm 163 of a bell crank 164 also pivotally carried on the pin 153, as shown in Figs. 4 and 11. The arm 163 carries a cam follower 166 which is biased by a spring 169 into engagement with one cam path 167 of a star cam 168, the cam path having alternate high and low spots and acting through the follower 166 and arms 163 and 157 to turn the arm 154 to engage the pawl 64 and prevent it from engaging the ratchet wheel 72 on alternate operating movement of the actuator 60. The star cam 168 is rotatably mounted on a shaft 170 also fixed in the end frame 22 and is turned step by step by means of a ratchet wheel 171 secured to the star cam and a pawl 172 carried on one arm of a lever 173 pivotally carried on the shaft 170, Figs. 2 and 4. The lever 173 is connected by a link 176 to the axle 56 so that upon each operating movement of the lever 52 and actuator 60, the link 176 operates the lever 173 to move the pawl 172 and advance the ratchet wheel 171 one tooth which moves either a high or low spot of cam path 167 into engagement with the follower 166. A second arm 177 of the bell crank 164 carries a member 178 adapted to engage and prevent pawl 58 from engaging the teeth of the ratchet wheel 66 (Figs. 11 and 12) every other operation of the actuator 60 for purposes hereinafter set forth.

As hereinbefore set forth, the arm 156 of lever 150 engages the pawl 62 to hold it out of engagement with the ratchet wheel 70 when widening movements occur in a narrowing cycle of the machine. For this purpose a second arm 182 of the bell crank 150 carries a follower 183 which is held in engagement with a second cam path 186 of the star cam 168 by a spring 187. The cam path 186 has low cam spots aligned with certain of the low spots of the cam path 167, alternating with high spots which have a length equal to a three tooth movement of the ratchet wheel 171 or two high and one low cam spots of cam path 167. Therefore, the cam path 186 of the star cam 168 will act through the follower 183 and bell crank 150 to permit the pawl 62 to engage the ratchet wheel 70 for one operating movement of the actuator 60 and hold the pawl out of engagement with the ratchet wheel during three operating movements of the actuator as hereinafter set forth.

At the beginning of a series of widening operations in accordance with the invention, and with the end stops 36 and transfer or narrowing points in predetermined positions relative to each other and the pawl 172 in engagement with its ratchet

wheel 171, the rod 106 is given the longer of its shifting movements to align the follower 48 with the cam 46, and turn the plate cams 78 and 80 to the positions of Fig. 2. At this time the follower 166 is on a high spot of its associated cam path 167 (Fig. 11) to disable the pawl 64 and follower 183 is on a low spot of the cam path 186 (Fig. 1). As the machine is operated to knit a course of loops, the actuator is operated by the cam 46 and the pawl 62 is free to act to turn its spindle and the end stops 36 two needles in the widening direction. During the operating movement of the actuator 60 the cam 168 is turned a distance equal to one tooth of ratchet wheel 171 to move a low spot of cam path 167 beneath the follower 166 and a high spot of cam path 186 beneath the follower 183 as shown in Fig. 2. Also, during this revolution of the camshaft 20, the rod 106 is returned to the position shown in Fig. 6 but is immediately given the shorter of its different length movements which again turns the plate cams 78 and 80 to the position of Fig. 2. In the next revolution of the camshaft, which is a revolution in which the camshaft has been shifted to the narrowing position, as the actuator 60 is raised, the spindle 38 is given a one needle movement in the widening direction by the pawl 64, to move the narrowing points outwardly a one needle distance, and the bell crank 150 holds the pawl 62 away from the ratchet wheel 70. During this operating movement of the actuator 60 the star cam 168 is turned another one tooth distance to move a high spot of cam path 167 beneath follower 166 to disable pawl 64 and the follower 183 remains on a high spot of the cam path 186 to maintain the pawl 62 in disabled position. In the next revolution of the camshaft 20, a plain course of loops is formed in which no widening occurs. During formation of this course the rod 106 is given another of its longer movements to shift the follower 48 into the plane of the cam 46 and to move the cam plates 78 and 80 to the positions of Fig. 2. During formation of the course of loops in the next revolution of the camshaft 20, with the followers 166 and 183 on high portions of their associated cam paths of the star cam 168, both pawls 64 and 62 are held inactive with respect to their associated ratchet wheels 72 and 70, respectively, so that on the upstroke of the actuator 60, neither of the spindles 38 and 34 will be turned. During the operation of the actuator 60, the ratchet wheel 171 is turned another tooth which moves a low spot of cam path 167 beneath follower 166 and the follower 183 remains on the high portion of cam path 186. In the next revolution of the camshaft 20, which is a revolution in which the camshaft is shifted to the narrowing position, on the upstroke of the actuator 60 the spindle 38 and the associated narrowing points are given another one needle movement in the widening direction. With this second one needle movement the points and end stops are again in their predetermined relation. During the latter operation of the actuator 60, the cam 168 is advanced another step which moves a high spot of cam path 167 beneath the follower 166, to disable pawl 64, and a low spot of cam path 186 beneath the follower 183 whereby the parts are again in position for the next of the series of widening operations.

For two needle narrowing, which usually follows the widening operations when making a stocking blank on the machine shown, star cam 168 is disabled by moving pawl 172 into an inop-

erative position relative to the ratchet wheel 71. This is done when the follower 166 is on a low spot of cam path 167 so that member 178 will not interfere with the action of narrowing pawl 58. The positions of lever 150 and follower 183 and of lever 148 will not be important because, for narrowing operations, cams 78 and 80 will not be turned out of the positions for narrowing and will hold widening pawls 62 and 64 out of action regardless of the disabling levers. Also during two needle narrowing, the plate cam 77, pivoted on spindle 38, is held in the position shown in Figs. 13 and 15, by means hereinafter set forth, so that the plate cam will not interfere with the pawl 61 and therefore the pawl operates spindle 38 a two needle distance.

In a portion of the stocking where two needle narrowing is employed it is also the custom to incline some of the narrowing lines toward the selvages. For this purpose, each fashioning means or head of the usual full-fashioned knitting machine is provided with one of the pawls 71, hereinbefore set forth, which is adapted to act on the ratchet 72 on spindle 38 to turn the spindle one needle in back-racking or widening direction on the downstroke of the actuator 60 and pawl 71 after certain of the narrowing operations. Throughout a considerable portion of the period occupied in knitting a stocking blank, pawl 71 is held out of action by a link 188, the left end of which, as viewed in Figs. 1 and 2, is pivoted to the lower end of an arm 190 which depends from and is fixed to a shaft 191. Shaft 191 is adapted to be turned clockwise as viewed in Fig. 1 by a slider piece 192 fixed on the outer or rear free end of an arm 193 which embraces shaft 191 and has its inner or forward end connected to the nut 37 on spindle 34 in the usual manner. Slider piece 192 is adapted to coat with cam pieces 196, 197 and 198, shown in Fig. 4, fixed on a member 201 one end of which is carried on the arm 190 and the other end on a member (not shown) also fixed on the shaft 191. When slider piece 192 contacts either of the cams 196, 197 or 198, the arm 190 holds the pawl 71 away from its ratchet wheel 72, as shown in Figs. 1 and 2. However, the slider piece 192 moves lengthwise of shaft 191 with nut 37 and, at times disengages the cams 196, 197 and 198 whereby a spring 202, connecting the arm 190 and pawl 62, draws arm 190 counterclockwise to permit, other things being suitably placed, a spring 204 connecting the pawls 64 and 71 to draw the pawl 71 into engagement with the ratchet wheel 72 to back-rack spindle 38 on the downstroke of the pawl in the usual manner. A throw over arm 203 fixed on the rod 84, connecting the cams 78 and 80, is provided to at times prevent engagement of the pawl 71 with the ratchet wheel 72 irrespective of the relation between slider piece 192 and cams 196, 197 and 198. When the pawl 71 is to operate as in the diamond point toe, the arm 203 is positioned as shown in Fig. 2. However, when the pawl is to be held inactive throughout the knitting of a stocking blank, the arm 203 is moved to the position shown for illustrative purposes only in Fig. 1. The structure of the device of which arm 203 is a part and the function thereof is more fully set forth in Haehnel, U. S. Patent No. 2,432,413, of 1947, and not forming a part of the present invention is not described further herein.

Cams 196, 197 and 198 also control the action of the pawl 62 during certain fashioning or other loop transferring operations of the machine

through a link 206 which connects the arm 190 and the pawl 62. When the slider piece 192 is on the cam 196, the position of the parts at the start of the stocking blank, the arm 190, through the link 206, will hold the pawl 62 away from the ratchet wheel 70 irregardless of whether the plate cam 78 is in its position of Fig. 1 or Fig. 2. When the slider piece is on the cam 197, which is lower than the cam 196, the position of the parts at the start of the heel widening, the arm 190 is turned sufficiently in a counterclockwise direction to permit engagement of the pawl 62 and ratchet wheel 70, when the plate cam 78 is in the position shown in Fig. 2 and the bell crank 150 is in its position of Fig. 1. After reaching the widest part of the heel the points continue to transfer certain of the heel loops outwardly without actually widening the fabric at which time the slider piece has again been moved to engage the cam 196. With the parts in this position the pawl 62 will be held away from the ratchet wheel 70 although the pawl 64 continues to rack the spindle 38 outwardly. The cam 196 contacts the slider piece 192 in the latter part of the diamond point narrowing and being the same height as the cam 196 also acts to hold pawl 62 away from the ratchet wheel 70 if the cam 78 is accidentally moved to the position of Fig. 2.

During the production of the welt and after-welt of stocking blanks, it is often desirable to form picot or lace stitches. During the formation of such picot or lace stitches, which occurs when the camshaft 20 is shifted into narrowing position, a button on the pattern chain causes the rod 106 to shift through the shorter of its movements which shifts the cams 78 and 80 to the position shown in Fig. 2 to hold the narrowing pawls 58 and 61 away from their respective ratchet wheels. At this time the slider piece 192 is in engagement with the cam 196 which holds the pawl 62 away from the ratchet wheel 70 and a finger 207 (Fig. 1) secured to the nut 39 (securing means not shown), holds the pawl 64 away from the ratchet wheel 72.

As hereinbefore set forth, when forming single needle narrowings in the stocking blank, the plate cam 77 is adapted to hold the pawl 61 away from the first tooth of the ratchet wheel 68 but permits the pawl to engage the second tooth in the movement of the pawl to turn the spindle 38 a one needle distance. The plate cam 77 is normally employed to act as a safety means to provide a predetermined limit to the movement of the nuts 39 toward each other. In Figs. 13 and 15 the plate cam 77 is shown in its position to permit the pawl 61 to engage the ratchet wheel 68 and turn the spindle 38 a two needle distance. In this position a surface 210 of plate cam 77 is held in engagement with a rod 211 by a spring 212. The rod 211 is carried in fixed parts of the machine for sliding movement parallel to the axis of the spindle 38 and is biased to the left as viewed in Fig. 3 by a spring 215, to the position shown in Fig. 15. The rod 211 is limited in its leftward movement by a collar 216, fixed to the rod, by engagement of collar 216 with a portion 214 of one of the bearing brackets for the spindle 38, as shown in Fig. 3. The rod 211 also has fixed thereto a collar 217 adapted to be engaged by the nut 39 when the nut is moved toward the right, as viewed in Fig. 3, beyond its predetermined limit. If the nut 39 is inadvertently moved beyond said predetermined limit, the nut engages the collar 217 to move the rod 211 to the right from its position beneath the plate cam 77,

whereby the plate cam is turned in a clockwise direction until a pin 220 in the plate cam engages the rod 211, in which position a high cam surface 221 of cam 77 has been moved into the path of the pawl 61 to thereby prevent further engagement between the pawl and ratchet wheel 68. When the nut 39 is returned to its normal path of movement, the plate cam 77 may be returned to its position of Fig. 13.

To hold the pawl 61 out of engagement with the ratchet wheel 68 during one tooth of the normal two tooth movement of the pawl, a cam surface 222 of the plate cam 77 is moved into the path of the pawl 61, as shown in Fig. 11. In order to position the surface 222 in the path of pawl 61 the rod 211 is moved to the right to its position in Fig. 14 whereupon the cam 77 is biased in a clockwise direction to move a stepped surface 225 into engagement with the rod 211, as shown in Figs. 11 and 14. When the single needle narrowings are completed, the plate cam 77 is manually turned in a counterclockwise direction to the position of Fig. 13 to move the surface 222 out of the path of the pawl 61, whereupon the spring 215 moves the rod 211 to the left from its position in Fig. 14 to its position in Fig. 15, the latter position being determined by the collar 216.

In the operation of the machine, the plate cam 77 is positioned as in Fig. 11 for forming single 30 needle narrowings throughout the leg portion of the blank. After the final leg narrowing the plate cam is turned counterclockwise with the rod 211 moving to the position of Figs. 15 as hereinbefore set forth. With the plate cam in such position, two needle narrowings will be formed throughout the remaining narrowed portions of the blank. On the last two needle narrowings movements of the spindle 38 and nuts 39 at the end of the toe of the blank, the left nut 40 39 engages the collar 217 and moves the rod 211 to the right sufficiently to permit a clockwise movement of the plate cam 77 to its position of Figs. 11 and 14 for the start of the next blank. If for some reason the blanks are destroyed or pressed off the needles before completion of the blanks, particularly at a point in the blank prior to the start of the toe narrowing, the nuts 37 and 39 are reset to starting position for the start of the next blanks without, however, resetting the rod 211 for forming single needle narrowings as hereinbefore set forth. Under these conditions, after the nuts 39 are reset to starting position the rod 211 is manually moved to the right, as viewed in Fig. 3, to release the plate cam 77 to its position of Fig. 14, a collar 226 on the rod engaging the nut 39 to limit such manual movement of the rod.

When forming single needle narrowings, the pawl 58 for turning the spindle 34 in the narrowing direction must be held out of engagement with the ratchet wheel 66 on alternate operations of the actuator 60 to maintain the spindle 34 in relation with the spindle 38. For this purpose there is provided the member 178 which is alternately operated to engage the pawl 58 to hold it away from the ratchet wheel 66 or to release the pawl for cooperation with the ratchet wheel, as hereinbefore set forth, as determined by the cam path 161 of the star cam 168.

In machines of the type shown, the spindles 34 and 38 are provided with means for preventing overtravel of the spindles during turning movement of the spindles as determined by the pawls 58, 62 and 61, 64, respectively. For this

purpose, the spindle 34 has a disk 228 having notches engageable by a detent member 229 and the spindle 38 has a disk 231 thereon having notches engageable by a detent 232. Due to the shape of the notches in the disk 228 and the end of the detent 229 cooperating with said notches it is necessary to raise the detent at each upward movement of the actuator 60. For raising detent 229 a cam member 234 (Fig. 4) carried on the lever 14 (Fig. 2) engages a pin 236 which engages a lever 238 connected to the detent 229. As the actuator 60 rises the lever 14 turns on the spindle 34 and cam 234 engages pin 236 to turn the lever 238 in a counterclockwise direction to thereby raise the detent 229 out of engagement with the disk 228. A spring 239 returns the detent 229 into engagement with the disk when the cam 234 disengages pin 236.

The spindle 34 is also provided with means for preventing accidental turning of the spindle in the widening direction due to the impact of the carrier rods on the end stops 36. Said means comprises a pawl 240 carried on the shaft 191 and which is adapted to engage the teeth of ratchet wheel 66. The pawl 240 is disengaged from the ratchet wheel on each upward movement of the actuator, to permit turning of the spindle in the widening direction, by a latch 242 which engages a pin 243 carried on the pawl. The latch 242 is carried on an arm 245 fixed to and adapted to turn with the lever 14. The pawl 240 is provided with an arm 246 which is connected to the pawl 58 by a link 248, the link having a slotted connection with the arm to permit the normal functions of both pawls. The link 248 is so constructed to permit pawls 58 and 240 to be simultaneously moved to inactive positions during resetting of the spindle 34.

The operation of the mechanism hereinabove described will be apparent from the foregoing. However, for purposes of convenience, and to emphasize the novel features of the present method invention, the operation of the apparatus shown will be further described as follows:

When a stocking blank or similar flat knit article has been knitted to a point at which it is desired to perform a widening operation, a combination according to the invention of yarn carrier action and transfer point action is employed. In so doing, the end stop spindle 34 is operated 45 during a knitting revolution of the main cam-shaft 20, that is to say one in which the yarn carrier is operated to lay yarn, to move the end stops 36 outwardly a two needle distance, the spindle 38 for the transfer points being maintained stationary during this revolution. In the next revolution, the end stop spindle 34 and the yarn carrier are kept stationary but the point spindle 38 is turned to move the loop transfer points outwardly a one needle distance. In a subsequent revolution, the point spindle is given a second one needle outward loop transferring movement so as to maintain the original relation of the points to the selvages. Moreover, in the particular apparatus shown for carrying out the present novel widening method disabling levers 148 and 150 are employed which are controlled and operated by cam paths 167 and 186 of star cam 168, which in turn is operated from the actuator 60, for moving the widening pawls 62 and 64 for racking the spindles, and which cause the appropriate widening pawl to be thrown out of action when the other pawl is to operate. The cam 168 is given an idle movement between said first and second movements of the

point spindle in a revolution of the main cam-shaft in which neither spindle is turned to position the cam paths properly for the second effective movement of the point moving spindle. Said idle movement of the cam 168 involves an operation of the actuator but no movement of the spindles occurs as a result of this operation because the star cams are then both in position to cause their disabling levers to prevent strokes of their pawls from affecting the spindles. Said idling movement of the actuator can conveniently be completed during a knitting revolution in which the course to contain the second group of transferred loops is made. However, the invention is not limited to this in all cases. Such a widening repeat involves four operations of the actuator, the first during a knitting revolution of the cam-shaft of the machine to cause two needle widening movement of the end stops, the second during a narrowing cycle in the revolution of the cam-shaft following the widening movement of the end stops, to cause a one needle widening movement of the points, the third during a following knitting revolution to idly advance the star cam and the fourth during a narrowing cycle to cause the second one needle widening movement of the points. This repeat may be carried out as often as required to produce the desired widening of the fabric.

Following the widening of a stocking blank or other fabric being knitted, it is assumed that it will be desired to carry out two needle narrowing. This is done in the machine shown by the usual narrowing means, the means for producing widening or single needle narrowing being held in positions in which the usual movements of the narrowing pawls are not interfered with.

Following the end of the two needle narrowings, the stocking blanks are taken off the needles of the individual sections and the fashioning spindles manually reset so that another set of blanks may be begun, each of full width at the start. In blanks in which single needle narrowings are formed in the leg portion the rod 211 controlling the cam 77 is automatically reset on the last two needle narrowing of the previous set of blanks. Where two needle narrowings are formed throughout the stocking, the collar 217 is adjusted on the rod 211 so that the rod is only acted on to release the cam 77 when the nuts 39 are inadvertently moved toward each other beyond their predetermined limits. Upon its release by said rod, the cam 77 moves automatically to a position in which it blocks pawl 61 and through member 79, the pawl 58 to prevent further movement of the spindles in the narrowing direction. The cam 77 and rod 211 may again be positioned as in Figs. 13 and 15 when the nuts 39 have been reset to starting position. The subsequent change from narrowing to widening in the heel according to the present invention is controlled automatically by the pattern means through the medium of the plate cams 78 and 80 on the fashioning spindles and the disabling levers 148 and 150. In case single needle narrowing is used in the leg portion of the blank and it is desired to use two needle narrowing in the under part of the heel and remainder of the foot, the cam 77 for controlling the effective length of the stroke of the narrowing pawl 61 for the point spindle 38 is manually reset from the position of Fig. 11 to the position of Fig. 13 at any convenient time after the completion of the leg narrowings. However, the arrangement is such that

either two needle narrowing or single needle narrowing may be used throughout a blank or set of blanks as desired. Single needle widening is always used because it has been found that two needle widening movements of the transfer points places an undesirable tension on the loops and the control cam 80 for the point spindle is therefore shown as shaped to limit the effective length of the stroke of the widening pawl 64 to a one needle distance.

The operation of the remaining parts of the machine shown affects the invention only indirectly, if at all, and will not be described in detail.

15 Of course, the improvements specifically shown and described by which I obtain the above results, can be changed and modified in various ways without departing from the invention herein disclosed and hereinafter claimed.

20 What I claim is:

1. In a straight knitting machine operating in knitting and fashioning cycles, the combination of yarn carrier rods and movable end stops therefor, loop transferring points and a fashioning mechanism including said rods, stops and points, said mechanism adapted when thrown into action to move said stops in the widening direction during a knitting cycle while preventing movement of the points and to operate the points to transfer loops outwardly in a succeeding cycle of the machine while preventing movement of said end stops.

2. In a straight knitting machine operating in knitting and fashioning cycles, the combination of yarn carrier rods and movable end stops therefor, loop transferring points and a fashioning mechanism including said rods, stops and points, said mechanism adapted when thrown into action to move said stops in the widening direction during a knitting cycle while preventing movement of the points, and to operate the points to transfer loops outwardly in a fashioning cycle while preventing movement of said end stops.

3. In a straight knitting machine having a revolving cam-shaft, fashioning mechanism comprising spindles for moving end stops for yarn carrier rods and for moving points for transferring loops, respectively, narrowing pawls and widening pawls for said spindles, pattern means, means activated by said pattern means for moving said pawls simultaneously to rack said spindles, means to hold one set of pawls inactive while the other set acts to turn said spindles and means for holding the widening pawl for the point spindle inactive while permitting action of the pawl for moving the end stops outwardly in a knitting revolution of the cam-shaft and adapted to hold the widening pawl for the end stops inactive and permit operation of the pawl for moving the points outwardly during a fashioning revolution of the cam-shaft.

4. In a straight knitting machine having revolving parts, the combination of yarn carrier rods and movable end stops therefor, loop transferring points and a fashioning mechanism including said rods, stops and points, said mechanism adapted when thrown into action to move said stops in the widening direction during a yarn laying stroke of a carrier rod while preventing movement of the points and to operate the points to transfer loops outwardly while preventing movement of the stops and in successive revolutions of the machine.

5. In a straight knitting machine, the combination of fashioning mechanism comprising

spindles for moving end stops for yarn carrier rods and for moving points for transferring loops, respectively, narrowing pawls and widening pawls for said spindles, a pattern means, control means whose movements are determined by said pattern means for moving the narrowing pawls to inactive position when a widening operation is to take place and for moving the widening pawls to inactive position when a narrowing operation is to be performed, a lever adapted to prevent operation of the end stop spindle by its widening pawl by disabling the pawl at a time it is freed by said control means, star cam means moving said lever into disabling position at every second, third and fourth operating stroke of the pawl, a second lever adapted to prevent operation of the point comb spindle by its widening pawl by disabling the pawl at a time it is freed by said control means, and star cam means moving said second lever into disabling position at every other one of the operating strokes of the pawl.

6. The method of operating a knitting machine having fabric fashioning means including a revolving camshaft, end stops for yarn carrier rods, a pair of spindles, one for moving said stops and the other for moving loop transferring points and means adapted when thrown into action to turn said spindles in either direction, comprising turning one of said spindles to move said stops in the widening direction during a knitting revolution of the camshaft while the other spindle is idle and turning the other of said spindles to transfer loops outwardly while said one spindle is idle in a non-knitting revolution of said camshaft.

7. The method of operating a knitting machine having a revolving camshaft, a spindle for moving loop transferring points, end stops, a spindle for moving said stops, said spindles operated from said camshaft and means adapted when thrown into action to turn said spindles in either direction, comprising moving said stops in the widening direction during a knitting revolution of said camshaft while said spindle for the transfer points is idle and moving said spindle for the points to transfer loops outwardly while said one spindle is idle in a non-knitting revolution of said camshaft, said movements falling in successive revolutions of the camshaft.

8. The method of operating a knitting machine having a revolving camshaft, a spindle for loop transferring points, end stops for a yarn laying carrier operated from said shaft and means adapted when thrown into action to turn said spindle in either direction, comprising moving said stops in the widening direction during a knitting action of said camshaft while the spindle for the point combs is idle and moving said spindle to transfer loops outwardly at a time said stops are idle, said movements falling in immediately successive revolutions of the camshaft.

9. The method of operating a knitting machine, in knitting and fashioning cycles, having fabric fashioning means including a yarn carrier, end stops, loop transferring points, a pair of spindles, one for moving said stops and the other for moving said points and means adapted when thrown into action to turn said spindles in either direction, comprising turning one of said spindles to move said stops for the yarn carrier in the widening direction during a knitting cycle while the transfer points are idle, turning the other of said spindles to move said points to transfer loops outwardly during a fashioning cycle while said

stops are idle, and turning said spindle simultaneously to move said stops and said points in the direction to narrow the fabric during a fashioning cycle.

5 10. In a straight knitting machine having a revolving camshaft, fashioning mechanism comprising spindles for moving end stops for yarn carrier rods and for moving points for transferring loops, respectively, narrowing pawls and widening pawls for said spindles, pattern means, means thrown into action by said pattern means for moving said pawls simultaneously in the direction to rack said spindles, a control means normally positioned to prevent one group of said pawls from acting on their spindles and controlled by said pattern means to permit said one group of pawls to turn the spindles and to prevent the other group from so doing, and means actuated by said pawl moving means during a knitting revolution of the camshaft permitting the widening pawl for the stop spindle to turn it while preventing the widening pawl for the point spindle from turning it, said last means also preventing the widening pawl for the stop spindle from turning it during the next three revolutions in which the pawls are moved in racking direction while permitting the widening pawl for the point spindle to move it during the first and third of said next three revolutions.

20 30 11. In a straight knitting machine, the combination of an end stop spindle, a point moving spindle, pawls for said spindles, a lever adapted to hold out of action the widening pawl for the point spindle, a lever adapted to hold out of action the narrowing pawl for the end stop spindle, a star cam having a step-by-step movement, a follower for the cam journaled on one of said levers, said levers arranged to be moved simultaneously by movements of said follower to hold their pawls out of action and to permit them to operate, and cams acting to hold out of action either said widening pawl or said narrowing pawl when they both have been freed by their levers.

40 45 12. In a straight knitting machine having a revolving camshaft, the combination of an end stop spindle, a point moving spindle, pawl and ratchet means for turning said spindles in the narrowing or widening directions as desired, a lever adapted to hold the widening pawl for the point spindle away from its ratchet, a lever adapted to hold the narrowing pawl for the stop spindle away from its ratchet, a lever adapted to hold the widening pawl for the stop spindle away from its ratchet, star cam and follower means acting on said first two levers to hold said first widening pawl and said narrowing pawl out of action simultaneously, and star cam and follower means acting on said last lever to hold the widening pawl for the stop spindle out of action in the revolutions in which the other widening pawl turns the point spindle.

50 55 60 65 70 75 13. In a straight knitting machine having a revolving camshaft, the combination of pattern means, an end stop spindle, a point spindle, and racking means for said spindles including two cams on said camshaft, a follower adapted to contact with one or the other of said cams in either knitting or non-knitting revolutions of the camshaft, a pattern controlled means to shift said camshaft in non-knitting revolutions of the shaft, and means to shift said follower in knitting revolutions only comprising a lever biased to turn in one direction and normally restrained by a pattern controlled lever and a second pat-

tern controlled lever acting to intercept said first lever to prevent it from making a full stroke in non-knitting revolutions.

14. The method of operating a knitting machine during knitting and non-knitting cycles, said machine having fabric fashioning means including an end stop spindle and a point spindle and means adapted when thrown into action to turn said spindles in either direction, comprising turning said stop spindle to move the stops in the widening direction during a knitting cycle while the point spindle is idle, turning said point spindle to transfer loops outwardly in a non-knitting cycle while the stop spindle is idle, and turning both said spindles in the narrowing direction in a non-knitting cycle.

15. The method of operating a knitting machine during knitting and non-knitting cycles, said machine having fabric fashioning means including an end stop spindle and a point spindle and means adapted when thrown into action to turn said spindles in either direction, comprising turning said stop spindle to move the stops in the widening direction during a knitting cycle while the point spindle is idle, turning said point spindle to transfer loops outwardly in a non-knitting cycle while the stop spindle is idle, and turning the point spindle again but in the narrowing direction in a non-knitting cycle when the stop spindle is idle.

16. In a straight knitting machine, the combination of a revolving camshaft having a position for knitting and a position for fashioning, a yarn carrier rod and movable end stops therefor, loop transferring points, spindles for moving said stops and points, respectively, narrowing pawls and widening pawls for said spindles, pattern means, means thrown into action by said pattern means for racking said spindles by said pawls, control cams normally positioned to prevent one group of said pawls from acting on their spindles, and means controlled by said pattern means to position said control cams to permit said one group of pawls to turn the spindles and to prevent the other group from so doing, said racking means having two cams on said camshaft and a follower adapted to coact with either one of said cams, said positioning means having a lever acting to shift said follower and a rod for moving said lever and making strokes of different lengths of which only the longer is effective to shift the follower but all of which move said control cams the same amount, and a pattern controlled member acting to restrict the length of stroke of said rod.

17. In a straight knitting machine, the combination of a revolving camshaft having racking cams thereon, a cam follower for transmitting racking impulses from said cams, narrowing pawls and widening pawls receiving said impulses, oscillatable cams adapted to be positioned to determine whether the narrowing or widening pawls shall be effective at the time of a given impulse from said follower, and a means for positioning both said oscillatable cams and said follower including a rod biased to move in a given direction along its axis and making strokes of different lengths, and connections from said rod to said follower and to said oscillatable cams comprising respectively a lever having a lost motion connection to the rod whereby the lever and follower are moved only by the longer strokes of the rod and a bell-crank lever having a follower, said follower engaging a cam

on said rod to move the oscillatable cams the same distance for each stroke of said rod.

18. The method of operating a straight knitting machine comprising a revolving camshaft having a position for knitting and a position for fashioning, two cams on said camshaft, a single follower for said cams, a pattern means, loop transferring points, a yarn carrier rod, stops for said rod, spindles for moving said stops and points, respectively, narrowing pawls and widening pawls for racking said spindles actuated by said shaft and control members for determining whether the narrowing pawls or the widening pawls will be effective in any given racking movement of the pawls comprising initiating a racking movement of said pawls by said pattern means in a knitting position of said camshaft, positioning said control members by said pattern means to cause the narrowing pawls to be ineffective, preventing racking of the point spindle during said knitting position of the camshaft, and initiating a second racking movement of said pawls by the pattern means in a fashioning position of said camshaft, positioning said control members by the pattern means to cause the narrowing pawls to be ineffective in said fashioning position of the camshaft, and preventing racking of the stop spindle during said fashioning position of the camshaft.

19. In a straight knitting machine having a main camshaft occupying a position in knitting and a further position in which fashioning is performed, the combination of a pattern means, an operating rod normally stationary, means activated by said pattern means adapted to move said rod a given distance along its axis, a cam follower having a lost motion connection with said rod whereby the follower is thrown into an active position by said rod during a knitting revolution of said shaft, control members for fashioning operations, an operating connection between said rod and said control members including a bell-crank lever having a cam follower journaled on one arm, and a cam fixed to the rod with which the follower on said lever engages to actuate the lever upon an initial movement of the rod and cam, said cam having a portion along which the follower travels upon further movement of the rod without further effect on said bell-crank lever.

20. In a straight knitting machine having a main camshaft occupying one position in knitting revolutions and another position in revolutions in which fashioning is performed, the combination of a pattern means, an operating rod normally stationary, means thrown into action by said pattern means adapted to move said rod a given distance along its axis, a cam follower having a lost motion connection with said rod whereby the follower is thrown into an active position by said rod during a knitting revolution of said shaft, control members for fashioning operations, an operating connection between said rod and said control members including a bell-crank lever having a cam follower journaled on one arm, a cam fixed to the rod with which the follower on said lever engages to actuate the lever upon an initial movement of the rod and cam, said cam having a face along which the follower travels upon further movement of the rod without further effect on said bell-crank lever, a member adapted to check the movement of the rod short of its full stroke, and a connection from said checking member to the pattern means for moving the checking

member into position to halt the movement of the rod.

21. In a flat knitting machine, the combination of a spindle having a nut thereon for moving transfer points, said nut having predetermined limits of movement in both directions on said spindle, a pawl and ratchet means adapted to turn said spindle in one of said directions in either two needle or one needle steps, a cam normally positioned to permit two needle turning movement of said spindle but adapted to control the pawl to limit it to a single needle movement of the ratchet, said cam also adapted when in a third position to prevent any action of the pawl on the ratchet, a rod for supporting said cam when in said first and second positions, and a stop member on said rod adapted to be moved to engage said nut when at its limit of movement in one of said directions to determine the position of said rod when said cam is in said second position.

22. In a flat knitting machine, the combination of a spindle having a nut thereon for moving transfer points, a pawl and ratchet means adapted to turn said spindle in a certain direction in either two needle or single needle steps, a cam normally positioned to permit said two needle turning movement of said spindle but adapted to be positioned to control the pawl to limit it to a single needle movement of the ratchet, said cam also adapted when in a third position to prevent any action of the pawl on the ratchet, a rod for supporting said cam when in said first and second positions and a stop on said rod adapted to engage a fixed part of the machine to determine the position of said rod when said cam is in said first position.

23. In a straight knitting machine, the combination of a spindle having a nut thereon for moving transfer points, said nut having predetermined limits of movement in opposite directions on said spindle, a pawl and ratchet means adapted to turn said spindle in one of said directions in either two needle or one needles steps, a cam normally positioned to permit two needle turning movement of said spindle but adapted to be positioned to control the pawl to limit it to a single needle movement of the ratchet, said cam also adapted when in a third position to prevent any action of the pawl on the ratchet, a rod for supporting said cam when in said first and second positions and a member on said rod adapted to be engaged by said nut to move the rod from supporting relation with said cam to permit it to move to said third position when the nut is moved in said one direction beyond said predetermined limit.

24. In a flat knitting machine, the combination of a cam, an actuating lever having a follower thereon and biased toward said cam, a pattern means, a second lever holding said first lever to prevent it from following said cam and controlled by said pattern means to release said first lever to permit it to follow said cam, said cam, follower and pattern means co-operating to restore said first and second levers to their holding relation, and a third lever also controlled by said pattern means and acting when desired to shorten the movement of said first lever in its biased direction.

25. In a straight knitting machine, the combination of an actuator, cam and follower means adapted to reciprocate said actuator when desired, end stops and loop transferring points, a pair of spindles, one for moving said stops and the other for moving said points, pawls adapted

to turn said spindles in the widening direction, pawls adapted to turn said spindles in the narrowing direction, operating connections between said pawls and said actuator for causing the pawls to turn the spindles when in positions for transmitting actuating impulses, a lever adapted to hold out of action the widening pawl for the point spindle, a lever adapted to hold out of action the narrowing pawl for the stop spindle, a cam and follower means adapted to move said levers to hold their said pawls out of action at the same time and to permit them to operate, the narrowing pawl for the point spindle acting to turn its spindle in the period said levers act to move their pawls out of action, and a cam acting in said period to limit the effective stroke of the narrowing pawl for the point spindle to half its maximum.

26. In a straight knitting machine operating in knitting and fashioning cycles, the combination of yarn carrier rods and movable end stops therefor, loop transferring points and a fashioning mechanism including, means to move said end stops in the widening direction during the knitting cycle, means for holding said points inactive during said widening movement of said stops, means to operate said points to transfer loops outwardly in a succeeding cycle of the machine, and means for holding said end stops inactive during movement of said points.

27. In a straight knitting machine operating in knitting and fashioning cycles, the combination of yarn carrier rods and movable end stops therefor, loop transferring points and a fashioning mechanism including, means to move said end stops in the widening direction during a knitting cycle, means for holding said points inactive during said widening movement of said stops, means to operate said points to transfer loops outwardly in a succeeding cycle of the machine, means for holding said end stops inactive during movement of said points, and means for controlling said moving and holding means for said end stops and said points.

28. The method of operating a knitting machine during knitting and non-knitting cycles, said machine having fabric fashioning means including an end stop spindle and a point spindle, pawls for said spindles, control means for said pawls and an actuator for said pawls, comprising controlling said pawls and operating the actuator to turn the stop spindle in the widening direction during a knitting cycle while the point spindle is idle, controlling said pawls and operating the actuator to turn the point spindle in the widening direction in a non-knitting cycle while the stop spindle is idle, controlling said pawls and operating said actuator in a knitting cycle while both spindles are idle and controlling said pawls and operating the actuator to turn the point spindle in the widening direction in a non-knitting cycle while the stop spindle is idle.

29. The method of operating a knitting machine during knitting and non-knitting cycles, said machine having fabric fashioning means including an end stop spindle and a point spindle, pawls for said spindles, control means for said pawls and an actuator for said pawls, comprising controlling said pawls and operating the actuator to turn the stop spindle a two needle distance in the widening direction during a knitting cycle while the point spindle is idle, controlling said pawls and operating the actuator to turn the point spindle a one needle distance in the widening direction in a non-knitting cycle while the

stop spindle is idle, controlling said pawls and operating said actuator in a knitting cycle while both spindles are idle and controlling said pawls and operating the actuator to turn the point spindle a second one needle distance in the widening direction in a non-knitting cycle while the stop spindle is idle.

30. In a straight knitting machine having a rotatable camshaft performing both knitting and non-knitting revolutions, and having yarn carrier rods, movable end stops for said rods, and rods supporting loop transfer points, the combination comprising a fashioning mechanism including rotatable spindles for moving said end stops and transfer point rods respectively, pawls for rotating said spindles, a pattern means, mechanism for operating said pawls, and a control means coacting with said pattern means to cause said pawl operating mechanism and pawls to move said end stops in a widening direction during a knitting revolution of the camshaft while holding said end stops against movement, and to move said transfer point rods in a widening direction in two succeeding but non-knitting revolutions of the camshaft while holding said end stops against movement.

31. In a straight knitting machine having a rotatable camshaft performing both knitting and non-knitting revolutions and having yarn carrier rods, movable end stops for said rods, and rods supporting loop transfer points, the combination comprising a fashioning mechanism including rotatable spindles for moving said end stops and transfer point rods respectively, pawls for rotating said spindles, a pattern means, mechanism for operating said pawls, and a control means coacting with the pattern means to cause said pawl operating mechanism and pawls to move said end stops in a widening direction during a knitting revolution of said camshaft and dur-

ing which yarn is laid for knitting while holding said transfer point rods against movement, and to move said transfer point rods to transfer loops outwardly in two succeeding but non-knitting revolutions of said camshaft while holding said end stops against movement, and to move both said end stops and said rods in a narrowing direction in a non-knitting revolution of the camshaft.

32. In a straight knitting machine, the combination of a camshaft, a cam thereon having a high point, a lever, a follower carried by said lever for contact by said cam, means for biasing said lever in a direction to cause said follower to contact said cam and follow the contour thereof, a sustaining member for holding said lever against movement by said biasing means, a pattern means, means controlled by said pattern means to move said sustaining member to its lever holding position when said follower is in contact with the high point of said cam, and a checking member under the control of said pattern means and movable into the position to check the movement of the lever and follower toward the cam.

HERBERT ERICH HAETHNEL.
